(57) **CLAIM**

The ornamental design for a diagnostic meter, as shown and described.

DESCRIPTION

FIG. 1 is a front perspective view of the diagnostic meter of our new design;

FIG. 2 is a rear view thereof;

FIG. 3 is a front view thereof;

FIG. 4 is a right side view thereof;

FIG. 5 is a left side view thereof; and,

FIG. 6 is a top view thereof.

The bottom of our diagnostic meter is not visible during normal use and does not form part of the claimed design.

1 Claim, 4 Drawing Sheets
